Stohler and Sisson.
Mower.

No. 28,313.

Patented May 15, 1860.

UNITED STATES PATENT OFFICE.

A. STOLER AND SAMUEL A. SISSON, OF BRISTOL, PENNSYLVANIA.

IMPROVEMENT IN HARVESTERS.

Specification forming part of Letters Patent No. 28,313, dated May 15, 1860.

To all whom it may concern:

Be it known that we, ABRAHAM STOLER and SAMUEL A. SISSON, both of Bristol, in the county of Bucks and State of Pennsylvania, have invented a new and useful Machine for Harvesting Grass or Grain; and we do hereby declare that the following is a full and exact description thereof, reference being had to the accompanying drawings and the letters of reference marked thereon, of which—

Figure 1 is side elevation; Fig. 2, a horizontal view, and Fig. 3 a perspective view, in all of which the same letters of reference apply to the corresponding parts of each figure.

A is the master-wheel, by which the gearing B C D is put in motion; *a*, Fig. 2, (removed in Fig. 1,) the carrying-wheel, running loose on same axle with master-wheel. These two wheels carry the forward end of the frame. G is a supporting-frame attached to the master-wheel axle and resting on the pivot or caster-wheel H; I, a fulcrum fastened to the supporting-frame G, projecting backward to connect with the lever K, which, in combination with the lever L, is used to elevate the rear of the frame, with the cutters, to pass over obstructions, or in traveling from place to place; M, a rod connecting lever L with the point of shoe S at O.

The shoe S is attached to the main frame F by means of the leg T. It is connected with the leg T by a bolt passing through both the foot Y and leg T, (marked N,) and on which it turns.

Now, the construction and operation of this machine are such that the driver, by depressing the end of lever K, brings the weight of the rear end of the frame by means of the fulcrum I upon the supporting-frame G and caster-wheel H, by which the shoe S and beam attached are elevated from the ground to any reasonable height for traveling or for passing over small obstacles. Again, in depressing the long arm of lever K the upright lever L is thrown backward and the rod M made to draw up the point of the shoe, thereby raising the point of the guards, rendering them less liable to catch in any grass or other occurring obstruction.

We claim—

1. The arrangement of the caster-wheel H, with its frame G, connected to the main axle, in combination with the levers K and L, fulcrum I, rod M, and shoe S, applied in the manner and for the purpose substantially as described.
2. The combination and arrangement of the rod M and levers interposed between the caster-wheel frame and pivoted shoe S for adjusting the cutting apparatus, substantially as described.

ABRAHAM STOLER.
S. A. SISSON.
